(57) **CLAIM**

The ornamental design for an end link for a watch, for use in coupling a watch strap to a base of the watch, as shown and described.

DESCRIPTION

FIG. 1 is a perspective view of an end link for a watch, for use in coupling a watch strap to a base of the watch, in accordance with our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of the end link of FIG. 1 and illustrating an example environment in which the end link may be used, whereby the end link is shown coupling a watch strap to a base of a watch.

The details shown in broken lines are for illustrative purposes only and form no part of the claimed design.
